Primary Examiner — Alison M Ofstun(57) **CLAIM**

The ornamental design for a hair remover, as shown and described.

DESCRIPTION

FIG. 1 is a perspective view of a hair remover showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the hair remover, shown with the cap on; and,

FIG. 10 is an enlarged view of the encircled portion 10 of FIG. 1.

The evenly spaced broken lines in the drawings illustrate portions of the hair remover that form no part of the claimed design. The dot-dash broken lines illustrate enlarged view indicators and form no part of the claimed design.
